UNITED STATES PATENT OFFICE

172,444

BRACELET

William Ruser, Beverly Hills, Calif.

Application April 27, 1953, Serial No. 24,682

Term of patent 3½ years

(Cl. D45—4)

To all whom it may concern:

Be it known that I, William Ruser, a citizen of the United States and resident of Beverly Hills, county of Los Angeles, State of California, have invented a new, original, and ornamental Design for Bracelet, of which the following is a specification, reference being had to the accompanying drawing forming a part hereof, in which:

Fig. 1 is a front elevational view of a bracelet, showing my new design;

Fig. 2 is a rear elevational view thereof; and

Fig. 3 is a bottom plan view thereof.

I claim:

The ornamental design for a bracelet, substantially as shown.
